PISTON FOR FOUNTAIN PENS

Bernt Nilsen, Barranquilla, Colombia

Application June 17, 1948, Serial No. 33,497

1 Claim. (Cl. 120—47)

1

The present invention relates to certain new and useful improvements in ink-filled fountain pens and has more particular reference to a suction developing piston and convenient, manually actuatable, operating means for the piston.

As the opening statement of the invention implies, many and varied types of piston structures have been devised by prior patentees and others to produce suction in a barrel and to thus suck ink, from a bottle or other container, into the storage reservoir of the barrel. The piston is arranged in most adaptations to reciprocate in or out and is operable by a rod or equivalent means to provide the desired degree of suction necessary to draw or suck ink into said reservoir. What is more, certain prior art fountain pens, in the category under advisement, utilize screw threads for imparting motion to the reciprocable piston. In carrying out the principles of the instant invention, I likewise rely on the principle of screwing the piston back and forth in the barrel in a manner to attain the desired ends with requisite certainty and efficiency.

More specifically, novelty is predicated upon an ink storing and delivering barrel, the bore of the reservoir of said barrel being screw threaded, the piston being threaded for operation in the stated screw-threaded bore and said piston being slidably keyed on a rotatable shaft whose rotation is accomplished by a thumb wheel or the like.

Other and more specific objects and advantages of the invention will become readily apparent from the following description and the accompanying illustrative drawings.

In the drawings, wherein like numerals are employed to designate like parts throughout the views:

Figure 1 is an elevational view, on a small scale, of a complete pocket-type fountain pen constructed in accordance with the principles of the present invention;

Figure 2 is an enlarged fragmentary sectional and elevational view on the line 2—2 of Figure 1, looking in the direction of the arrows; and

Figures 3, 4, 5 and 6 are cross sectional views on the lines 3—3, 4—4, 5—5 and 6—6, respectively, of Figure 2.

Referring now to the drawings by distinguishing reference numerals, the customarily shaped and proportioned barrel is denoted by the numeral 8 and this is open at opposite ends and internally screw-threaded, as at 9. One end of the barrel is fashioned into a reduced neck portion 10 which is externally screw-threaded to accommodate internal screw threads on a closing

2

gap 11 and is internally screw-threaded to accommodate external threads on a rubber or equivalent ring-nut 12. The ring nut is provided with a conical sleeve or bushing 13 which, in practice, serves to accommodate the cylindrical portion 14 of the piston rod. The upper end of the rod in Figure 2 is provided with a flange 15 which is swivelled in the nut and is further provided with a milled finger knob or grip 16 which is normally covered within the cap. The major portion of the turntable piston rod is oval in cross section as indicated at 17, and the piston, which is denoted by the numeral 18, has an oval bore which fits snugly on the rod and which permits the piston to work back and forth in an obvious manner. More specifically, the piston is in the form of a sleeve which is externally screw-threaded, as at 19, and said threads screw into the threads 9. The upper end of the piston is provided with a socketed collar portion 20 which serves to telescopically receive the bushing 13 when the collar portion is backed up against said bushing. The sleeve 13 is of the requisite degree of flexibility and tends to "pack" into the socket 20 in the collar 20 when the piston is at the extreme upper position. Thus, a substantially fluid-type seal is had which will prevent the leakage of ink between the piston and piston rod.

Assuming that the reservoir of the barrel is empty, the piston rod is turned by the thumb knob and the piston is screwed or fed forwardly or downwardly into the barrel to a desired or predetermined degree. Then, the pen 21 on the writing end of the barrel is dipped into the ink in the usual way and the piston rod is rotated in an opposite direction to develop suction in the reservoir between the pen 21 and the piston. The piston is progressively fed in the same direction until it comes into abutting contact with the bushing. The bushing telescopes into the socket of the collar 20 and when the piston is "home," rotation of the piston rod is stopped. The crowding or packing of the flexible bushing into the socket in the piston provides the desired ink seal and prevents leakage of ink.

In Figure 1, I have shown a suitable pocket clip 22 and in practice an appropriate closing cap (not shown) may also be provided.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even

though there is herein shown and described a preferred embodiment of the invention, the same is susceptible to certain changes fully comprehended by the spirit of the invention as herein described and within the scope of the appended claim.

Having described the invention, what is claimed as new is:

A fountain pen of the class described comprising an open-ended barrel having a cylindrical bore, the wall of said bore being screw-threaded, a sleeve defining a piston, said sleeve being externally screw-threaded and screwed into the screw threads of said bore and operable back and forth in the bore, the bore of said sleeve being oval in cross section, a piston feeding rod having a portion oval in cross section extending through the oval bore in said sleeve, said rod being located centrally in the bore of said barrel, a screw-threaded bushing screwed into one end of the barrel, said bushing having an axial cylindrical passage, said rod passing through and being rotatable in said passage, that portion of the rod passing through said cylindrical passage being cylindrical in cross section, a pen nib and ink-feeding means mounted for opera-

tion in the other end of said barrel, the end of said rod beyond the normal upper end of said barrel being provided with a thumb knob, said barrel terminating in an externally screw-threaded neck, and a screw cap threaded on said neck and enclosing said thumb knob, the upper end of the portion of the sleeve surrounding said rod being recessed and providing a socket, and the portion of said bushing surrounding said rod being reduced and adapted to telescope into said recess, whereby to effect a liquid-tight seal between the bushing and sleeve when latter are in positive abutting relationship.
